UNITED STATES PATENT OFFICE.

JOHN L. CRAIN, OF MAYSVILLE, ARKANSAS.

WIRE-STRETCHER.

SPECIFICATION forming part of Letters Patent No. 511,591, dated December 26, 1893.

Application filed May 15, 1893. Serial No. 474,221. (No model.)

To all whom it may concern:

Be it known that I, JOHN L. CRAIN, of the city of Maysville, Benton county, and State of Arkansas, have invented certain new and useful Improvements in Wire-Stretchers, of which the following is a full, clear, and exact description, reference being had to the accompanying drawings, forming a part hereof.

My invention relates to an improved wire stretcher and consists in the novel construction, combination and arrangement of parts, as will be more fully hereinafter described and designated in the claim.

The object of my invention is to provide an improved wire stretcher which shall be very simple in construction, effective in use and of low cost.

In the drawings: Figure 1 is a top plan view of the stretcher, with a part broken away. Fig. 2 is a sectional side elevation of the same. Fig. 3 is a perspective view of an auxiliary device used in carrying out the invention. Fig. 4 is a perspective view of a portion of a wire fence, and illustrating the operation of my invention.

1 indicates the body of the stretcher, which is preferably made of suitable size of malleable iron, or cast steel, in order to have the requisite strength.

20 I will preface my description by stating that the device is to be used as a lever in stretching the wire, having a sufficient length to exert the proper power. The body 1 at a point intermediate of its length is provided with a widened portion 2, in the upper face of which is formed a depression 3 having a smooth flat inner surface and an integral projection 4 which has a free inner end and overhangs a portion of said surface, and forms an open slot or recess 5 beneath said projection. The free end, or rather the outer end of the body 1 is provided with a sharp or attenuated point 6, so as to be readily driven into the wooden posts of the fence during use, and 45 said body from the widened portion 2 outward, tapers or is inclined.

7 indicates a grip-lever, the rear end of which extends a sufficient distance rearward to be within easy reach of the operator and is provided with a vertical handle 8, which is preferably formed by bending upward a portion of the lever until it occupies a position at a

right angle to the body of said lever. The forward and outer end of the grip lever is bent downward and outward and is provided with a gripping jaw 9 having flat and smooth upper and lower faces, and a rounded or curved free outer end or edge 10 which projects into and engages the slot 5 beneath the projection 4. The grip-lever 7 is pivotally connected to the body 1 at a point intermediate of its length, by means of a suitable rivet or bolt 11, so that the gripping jaw 9 is loosely mounted upon the flat surface of the depression 3, and is adapted to be drawn around as indicated by dotted lines in Fig. 1. The free outer edge 10 of the gripping jaw 9 is constructed to form a sort of cam, that is, it is not concentric with relation to the center of the pivot upon which the grip lever works. It is eccentric with relation to the base 12 of the slot or recess 5.

13 indicates the inner end of the body 1, which may be formed as here shown comparatively short and provided with an exterior screw thread, or it may be extended a sufficient distance to form a proper handle or lever, as no invention would be required to so extend it; or I may connect an ordinary piece of gas pipe 14 with this shank by means of a threaded coupling 15, in order to extend the length of the shank a sufficient distance. In other cases, an ordinary piece of gas pipe of sufficient size and length, may be loosely placed with its bore in engagement with said shank, and in such case the threads upon said shank would of course be omitted.

16 indicates a stay or brace used in carrying out the invention. It is preferably made of round iron with two parallel arms 17 at one end and an eye 18 at the opposite end. The outer ends of the arms 17 are free and provided with sharpened points 19, by means of which said arms may be readily pushed into the earth during use.

95 The operation is as follows: One end of the wire 20 having been made fast by means of a staple 21 or other device in common use for such purpose, the pointed end 6 of the body 1 is driven into a post 22 of the fence, or placed against said post and the free portion of the wire to be stretched is placed within the slot or recess 5 and the grip lever 7 is 100 swung around until it lies more or less par-

allel to the shank of the said body thereby gripping the wire between the eccentric edge of the grip-jaw and the base 12 of said slot and then the entire device is used as a lever with the post 22 as a fulcrum, properly to stretch said wire, said wire being firmly gripped between the eccentric edge 10 of said grip jaw and the base of said slot in the body of the stretcher. The overhanging projection 4 prevents the wire from slipping out laterally during the stretching operation. In the meanwhile, the stay or brace 16 has been placed in position with its eye 18 located upon the shank of the stretcher adjacent the inner end thereof, with its body inclined and with its arms 19 resting in contact with the ground. As soon as the operator has properly stretched the wire, the same will be held automatically stretched, by means of the brace 16 engaging the ground. All that he need do will be to push the sharpened arms 17 into the earth a sufficient distance to hold said brace in the position shown in Fig. 5, and he may then leave the stretcher in this position and walk back along the fence and secure the wire so stretched to the different posts by means of the staples 21 or other fastenings, and he may

then return and release the wire from the stretcher, and repeat the operation as often as desired.

30

I am aware that prior to my invention wire-stretchers have been constructed in the form of a lever having a sharpened end and arranged to stretch a wire by clamping the same between a fixed jaw and a movable jaw carried by the stretcher, and I do not broadly claim such.

35

What I claim is—

The combination, of a wire stretching device constructed in the form of a lever and provided with a movable clamping jaw to hold and stretch a wire, and an anchor 16 having two integral, parallel arms 17 pointed at their outer ends, and a circular eye 18 at the opposite end which loosely encircles and holds said lever, substantially as herein specified.

40

45

In testimony whereof I affix my signature in presence of two witnesses.

JOHN L. CRAIN.
